UNITED STATES PATENT OFFICE.

ALFRED SPRINGER, OF CINCINNATI, OHIO.

PROCESS OF TREATING TROLLEY-WIRES.

SPECIFICATION forming part of Letters Patent No. 706,699, dated August 12, 1902.

Application filed February 7, 1902, Serial No. 92,971. (No specimens.)

To all whom it may concern:

Be it known that I, ALFRED SPRINGER, a citizen of the United States, residing at Cincinnati, in the county of Hamilton and State 5 of Ohio, have invented new and useful Improvements in Processes of Treatment of Trolley-Wires, of which the following is a specification.

It is a fact of common knowledge that the 10 trolley-wires of electric railways deteriorate by continued use and become, in the parlance of the craft, "rotten" and "brittle," and thus break under the passage of the trolley-wheels or under sudden strains from various causes. This condition of deterioration 15 is supposed to be that or analogous to that of the molecular disturbance such as occurs in car-axles and other revolving shafts and parts of machinery under frequently-recurring stresses of the same character. The remedy for this condition in metals is usually reheating to such a temperature short of the fusion-point as will enable the molecules to reassume their normal relations; but 20 this remedy, while of easy application in the case of car-axles or small parts of machinery, in the case of trolley-wires in use is beset with difficulties so great as to render it impracticable in the ordinary manner or with ordinary 25 appliances. My invention seeks to overcome these difficulties and restore the molecular integrity of the trolley-wire without disturbing the wire in its operative relations and without interfering with the ordinary 30 uses of the railway. To this end I utilize the principle of heat development by imperfect or interrupted electrical contact at the wire by the passage thereover of a suitably-formed trolley-wheel or other contact device 35 40 by which an interrupted or imperfect return or earth circuit is formed and heat generated at such closely-recurrent intervals as by conduction and distribution bring the entire wire to the proper temperature, and thus by a process closely allied to annealing restore 45 the proper molecular condition of the wire as a whole.

In the drawings herewith illustrating the mode of applying the process indicated there 50 is shown, in—

Figure 1, a trolley-wheel rolling in contact

with the trolley-wire, and in Figs. 2 and 3 alternative forms of a trolley-wheel for producing a recurrently - interrupted circuit; Fig. 4, a diagrammatic figure indicating the 55 55 sparking-points and the distribution of heat by conduction.

The wheel A (indicated in Fig. 2) is one formed with alternate conducting and non-conducting segments or peripheral contact- 60 surfaces *c* and *b*, respectively. As the constructive details of such a wheel are commonly understood by electrical mechanics, further reference thereto will be unnecessary. The periphery of the wheel is continuously 65 circular, although successive arcs are of diverse conductivity, and it is well known that in rolling contact the circuit is alternately broken and restored, forming sparks of great heating power. The general effect is illus- 70 trated in the diagram Fig. 4, where the points *x* on the wire *w* (indicated by the lower vertical arrows) are those touched by the lines of division between conducting and non-conducting portions *c b* of the trolley-wheel A. 75 At such points the sudden "make and break" of the circuit, caused by the rolling contact of the wheel A, produces sparks of great heating power. The sudden and intense heat thus produced is by the heat conductivity of the 80 wire *w* transmitted in both directions, tending to meet at the points *y*, (indicated by the horizontal arrows,) thus tending to equalize the temperature of the wire as a whole. A substantially similar effect is produced by a 85 wheel A', Fig. 3, whose rolling periphery is divided into independent portions *c'*, interrupted by successive recesses *b'*, and the 90 sparking produced in substantially the same manner as before by interrupted electrical contact.

The degree of effect produced will obviously be governed by the intensity of the current transmitted and by the rapidity of the rolling motion of the trolley-wheel, both of which can 95 be determined by simple experiment under the local conditions of application.

In the case of copper, generally used for trolley-wires, an improved result is attained by sudden cooling of the wire after heating. 100 This may be effected by attaching to the trolley-arm *a*, Fig. 1, a follower or trailer consist-

ing of an open trough *e*, in which is mounted a wheel *g*, of absorbent material—such, for example, as “sponge-rubber”—formed in the general similitude of a trolley-wheel (indicated by dotted lines) and running partially submerged in water, which by a suitable pump (not shown) is kept in constant circulation in the trough from a cool source of supply through connecting-tubes *f f'*, carried through the trolley-arm *a*.

It is intended in the practical use of my invention to provide a special car suitably equipped with the necessary apparatus to run over the line at night or in the intervals of ordinary use at any time, and experience will soon determine the speed and other conditions necessary to be observed to secure perfect results.

The two forms of trolley-wheels here shown at *A* and *A'* are examples merely of various forms that may be used. Indeed, a sliding contact having a constant resistance or one capable of adjustment in degree may be used and the speed of travel regulated to raise the wire to the proper temperature. As all such details are within the common knowledge and skill of practical electricians, I do not deem it necessary to describe them further.

I claim as my invention and desire to secure by Letters Patent of the United States— 30

1. The method or process of restoring to normal molecular condition trolley-wires of electric railways deteriorated by use, consisting in treating the wire *in situ* at successive substantially adjacent points in its length by 35 a total or partial interruption of the circuit at each of said points in succession.

2. The method or process of restoring to normal molecular condition trolley-wires of electric railways deteriorated by use, consisting in treating the wire *in situ* at successive substantially adjacent points in its length by 40 a total or partial interruption of the circuit at each of said points in succession, and immediately thereafter cooling said wire to normal 45 temperature by means applied in similar succession to heated portions, substantially as set forth.

In testimony whereof I have hereunto set my hand in presence of two subscribing witnesses. 50

ALFRED SPRINGER.
